CONTAINER LABELING APPARATUS

Kurt Manrodt, Newark, N. J., assignor to Hoffman Beverage Company, Newark, N. J., a corporation of New Jersey

Application October 21, 1939, Serial No. 300,575

11 Claims. (Cl. 216—54)

This invention relates to labeling machines and has particular reference to improvements in the mechanism for operating the label grip finger for temporarily holding the label in the proper position on a container, preparatory to securing it in place thereon.

In one type of conventional container labeling machine, to which this invention particularly relates, an adhesive picker abstracts one or more labels from a stack of labels, swings into the path of movement of a container supported on a rotary table, lays the gummed label at the proper place on the surface of the container, and then a grip finger carried by the table moves into contact with the label to hold it in place as the picker is withdrawn, so that the label is properly positioned preparatory to being applied to the surface of the container by label wiping or brushing means. The grip finger is secured on a shaft journaled on the underside of the rotating table and is oscillated by a crank following the groove of a stationary horizontal cam and connected to the shaft by gearing. Usually there are several such cams for multiple type labeling machines, in which two series of containers are handled at the same time on a single rotary table. Due to the construction of these cams, and the arrangement of the shaft and other grip finger operating mechanism, the cam followers not infrequently lock in the cams and jam, resulting in breakage of the mechanism. Also, by reason of the long leverages and construction of the grip finger operating mechanism, only a slight resistance to movement of the grip finger may result in breakage of the gearing. Also, the construction of the mechanism makes it very difficult to remove a broken or faulty grip finger or its operating mechanism in case of breakage, thus resulting in inordinately long periods of disassembly of the machine.

In accordance with the present invention, the label grip finger operating mechanism is mounted on a bracket adjacent to the position of the finger beneath the edge of the rotary table. The grip finger is mounted on a horizontal shaft actuated by two followers resiliently held in engagement with the peripheries of corresponding flat disc cams, so as to follow the contours thereof. One of the cam followers is positively connected to a stub shaft coupled by gears to the horizontal grip finger shaft and the other is journaled on the stub shaft and connected to the first follower by a spring to eliminate backlash and provide some yielding to compensate for irregularities in the successive containers. Not

only does this arrangement permit ready assembly and repair of parts, but the cams are not self-locking under any conditions and free and smooth movement without vibration of the grip finger results. The cams, by reason of their construction and mounting on a fixed cam drum, may be readily adjusted angularly, and thus the operating positions of the grip finger may be varied at will, depending on requirements. With this arrangement, all of the objections to the unreliable, cumbersome, inaccessible grooved cam arrangements of the previous machine are eliminated, including the lack of facility of repair in case of damage.

For a more complete understanding of the invention, reference may be had to the accompanying drawings, in which:

Figure 1 is a plan view shown partly in section of a labeling machine fitted with the improved label grip finger operating mechanism of this invention;

Fig. 2 is a partial vertical section therethrough as seen along the line 2—2 of Fig. 1;

Fig. 3 is an enlarged horizontal section as seen along the line 3—3 of Fig. 2, showing the grip finger cam followers;

Fig. 4 is an enlarged axial section through the vertical grip finger actuating shaft, as seen along the line 4—4 of Fig. 3, and showing the mounting of the cam-following rollers thereon; and

Fig. 5 is an enlarged section through the cam adjusting means as seen along the line 5—5 of Fig. 1.

Referring to Fig. 1 of the drawings, numeral 10 designates a portion of the circular rotary table which is arranged horizontally on the upper end of a vertical drive shaft 11 to which it is keyed at 12 by a connecting sleeve 13, in turn keyed at 14 to shaft 11, as shown in Fig. 2. Sleeve 13 rests on a thrust bearing 15, supported on the upper end of the tubular center column 16 of the base 17 of the machine. The shaft 11 is journaled in column 16 and is continuously driven from a suitable source of power, not shown. Base 17 and its center column 16 remain stationary while driven shaft 11 rotates table 10 and its supporting sleeve 13 on thrust bearing 15.

The upper surface of table 10 is provided at its periphery with a plurality of container supports 19 upon which a container is placed by a suitable transfer mechanism, and on which it is held by a top gripping member 18, whose operating mechanism is not shown, but is conventional in construction, so that the container is firmly positioned on the support 19 throughout the

labeling operation. The edge of the table 10 in front of each container support 19 is provided with a tangential notch 21 into which the grip finger 20 moves from a substantially horizontal position shown in dotted lines in Fig. 1, to a substantially vertical position to grip the previously gummed label against the surface of the container in the manner described. In the particular form of labeling machine illustrated, the container to be labeled is a beverage bottle B, having body and neck labels, so that the grip finger 20 is provided with a body and neck label gripping pads 22 and 23, respectively. In such conventional machines the operations are of course synchronized, the bottle B being placed on the bottle support 19 and held there by the top gripping member 18, the label picker places neck and body labels in front of the bottle B, and then the grip finger 20 moves from the substantially horizontal position into a vertical position so that its pads 22 and 23 engage and hold the body and neck labels against the surface of the bottle in the manner described.

The grip finger 20 is secured by a screw 24 to a yielding bushing 25 connected by spring 27 to bushing 26, mounted on the outward end of a radially-extending horizontal shaft 30, the spring 27 affording self-adjustment of the finger to accommodate irregularities in the bottle. Shaft 30 oscillates in a bracket 31 secured by screws 32 to the under side of the rotary table 10. The screws 32 are readily accessible for the mounting and dismounting of the bracket 31. Connected to the free or inner end of horizontal shaft 30 is a coil spring 33 encircling the shaft 30 and connected at its other end to the bracket 31. The function of this spring will be explained later. Pinned on shaft 30 is a bevel gear 34 meshing with a bevel gear 35 journaled in bracket 31 on bushing 36 and pinned to vertical stub shaft 37, also journaled in bracket 31, as shown particularly in Fig. 2.

Journalled on the lower end of vertical stub shaft 37 is a double armed lever 38, one arm 39 of which carries a cam-following roller 40 and the other arm of which, 41, is recessed for the reception of one end of a coil spring 42, whose other end engages arm 43 of a similar lever 44 pinned to stub shaft 37, as shown particularly in Fig. 3. Fixed lever 44 also has a second arm 45 carrying at its end a cam-following roller 46, displaced vertically from roller 40. A plate 47 secured to the end of stub shaft 37 by a screw 48 and pin 49 within a counter-bore in the end of lever 38 holds the latter in place on shaft 37, as shown particularly in Fig. 4. Being journalled on stub shaft 37, lever 38 is yielding by reason of spring 42 connected to lever 44 which is fixed to stub shaft 37.

Fixed to the center column 16 of the machine is a large-diameter cam drum 50 having circular peripheral surfaces concentric with the axis of the machine. Encircling the cam drum and secured thereto by screws 51 over lock plates 51' is a cam ring 53. Screws 51 preferably pass through circumferentially-elongated slots 52 in cam ring 53 so that the latter may be adjusted axially on cam drum 50, as shown in Fig. 5. Also, as shown in Fig. 1, cam ring 53 is split diametrically into two parts, although it may be divided into more than two parts, so that it may be readily mounted on and dismounted from the cam drum 50.

Preferably formed integrally with cam rings 53 are two flat disc cams 54 and 55. Cam 54

has an edge contour such as is shown in Fig. 1, and is engaged by cam-following roller 40 of yielding lever 38 on stub shaft 37, while cam 55 has the contour shown in Fig. 1, and is engaged by cam-following roller 46 on lever 44 fixed on stub shaft 37. Similar cams 54' and 55' for the grip fingers of multiple labeling machines may be mounted in the same way on cam drum 50, the other operating mechanism for the grip finger remaining the same as that shown.

In operation of the labeling machine grip finger operating mechanism of this invention, the containers, such as bottles B, are placed on the bottle-supports 19 spaced around the periphery of rotary table 10, which is driven in a counter-clockwise direction, as shown in the arrow in Fig. 1, by driving mechanism connected to shaft 11. As the table 10 rotates, cam-following rollers 40 and 46 yieldingly engage the peripheries of corresponding disc cams 54 and 55, respectively, and since they are urged toward the center of the machine by spring 42, they are always in uniform constant engagement with their respective cams. The labels are delivered by the conventional picker, not shown, at the point indicated in the drawing by the legend "Delivery Station," and at that point the cam 55 has a rise, as seen in Fig. 1, which urges cam-follower 46 away from the center of the machine, turning stub shaft 37 in a counter-clockwise direction, as seen in Fig. 1.

This motion, communicated to shaft 30 by gears 34 and 35, causes the grip finger 20 to move from its normal substantially horizontal position, shown in dotted lines in Fig. 1, to a substantially vertical position so as to engage the bottle, so as to grip the neck and body labels with its respective pads 23 and 22 against the corresponding surfaces of the bottle. During this operation, cam-following roller 40 of yielding lever 38, in following the contour of cam 54, moves in substantially the opposite direction, that is, inwardly toward the center of the machine by reason of the drop in the contour of cam 54 adjacent the delivery station and substantially opposite the rise in cam 55, as shown in Fig. 1.

The movements of the two cam-following rollers 40 and 46 are accordingly substantially through the same angle, although in opposite directions, about the axis of vertical stub shaft 37.

As the table 10 continues to rotate, grip finger 20 holds the labels in position on the bottle B, until the label wiping devices have applied the labels permanently to the surface of the bottle. Thereupon, the cams 54 and 55 release grip finger 20 from the surface of the bottle. During this movement the fixed lever roller 46 engages a dip in cam 55 while the yielding lever cam-following roller 40 engages a rise in cam 54, thus turning the stub shaft 37 in a clockwise direction, as seen in Fig. 1, and consequently shaft 30 is turned so as to lower grip finger 20 below the surface of the table 10, the arc of movement of horizontal shaft 30 being approximately 95°.

In order to adjust the cams 54 and 55, holding screws 51 are loosened and the cam ring 53 shifted, as is permitted by slots 52. This adjustment does not disturb the relationship between cams 54 and 55 since they are both secured on cam ring 53, but it changes the relationship between cams 54 and 55 and corresponding cam-followers 40 and 46. The cams 54

and 55, by reason of their size and contour and position and the arrangement of their cam-following rollers, eliminate the danger of locking or jamming of the cam-following rollers thereon, so that smooth, positive operation of the label grip finger 20 results. In case of any backlash tendency between gears 34 and 35 during high speed operation of the machine, spring 33 serves as a retarding means so that the grip finger 20 can not suddenly swing forward in its upward movement by reason of any backlash between gears 34 and 35. In case, however, of any damage to the parts, they are readily accessible and the whole operating mechanism can be removed simply by removing screws 32, since all of the mechanism is carried on bracket 31 and the following rollers 40 and 46 need only be lifted from their corresponding cams 54 and 55. Replacement is equally simple, as will be readily understood. For duplex machines cams 54' and 55' are provided on cam drum 50 for operating the grip finger of the second delivery station.

While a preferred embodiment of the invention has been illustrated and described herein, it is to be understood that the invention is not limited thereto, but is susceptible of changes in form and detail within the scope of the appended claims.

I claim:

1. In a rotary container labeling machine having a moving horizontal container support, the combination of a movable finger on said support for holding a label on the container, a stationary cam mounted parallel to the plane of said support and having a peripheral cam contour, a lever pivoted about a vertical axis on the support, a cam-follower on the lever engaging the periphery of said cam and actuated thereby as the support moves relatively to the cam, means for adjusting said cam in said plane relatively to said lever to change the time of actuation of said lever, and operative connections between the lever and said finger for moving the latter into and out of engagement with the container.

2. In a rotary container labeling machine having a moving horizontal container support, the combination of a finger for holding a label on the container, stationary cam means, a shaft mounted for oscillation on said support, a pair of spaced cam-followers on opposite sides of said shaft, means resiliently connecting said levers for simultaneously engaging them with said cam means, operative connections between at least one of said levers and said shaft for oscillating said shaft during rotation of said machine, and operative connections between said shaft and said finger for moving the latter into and out of engagement with said container.

3. In a rotary container labeling machine having a moving horizontal container support, the combination of a finger for holding a label on the container, stationary cam means, a shaft mounted for oscillation on said support, a pair of spaced cam-followers, means resiliently connecting said levers for simultaneously engaging them with said cam means, operative connections between one of said levers and said shaft for oscillating said shaft during rotation of said machine, and operative connections between said shaft and said finger for moving the latter into and out of engagement with said container.

4. In a rotary container labeling machine having a moving horizontal container support, the

combination of a finger for holding a label on the container, stationary cam means, a shaft mounted for oscillation on said support, a pair of spaced cam-followers on opposite sides of said shaft simultaneously engaging said cam means, operative connections between one of said levers and said shaft for oscillating said shaft during rotation of said machine, means resiliently urging said followers into engagement with said cam means, and operative connections between said shaft and said finger for moving the latter into and out of engagement with said container.

5. In a rotary container labeling machine having a moving horizontal container support, the combination of a finger for holding a label on the container, stationary cam means, a shaft mounted for oscillation on said support, a pair of spaced cam-followers on opposite sides of said shaft simultaneously engaging said cam means, operative connections between at least one of said levers and said shaft for oscillating said shaft during rotation of said machine, means for adjusting said cam means angularly of the machine to change the time of actuation of the shaft by said cam-followers, and operative connections between said shaft and said finger for moving the latter into and out of engagement with said container.

6. In a rotary container labeling machine having a moving horizontal container support, the combination of a finger for holding a label on the container, a pair of stationary cams having peripheral cam contours in planes parallel to the plane of said support, a cam-follower engaging the contour of each cam, means resiliently urging said followers into engagement with the corresponding cam contours, a shaft mounted for oscillation on said support, means operatively connecting one of said levers to said shaft for oscillating the same as the machine rotates, and operative connections between said shaft and the finger for moving the latter into and out of engagement with the container.

7. In a rotary container labeling machine having a moving horizontal container support, the combination of a finger for holding a label on the container, a pair of stationary cams having peripheral cam contours in planes parallel to the plane of said support, means for adjusting said cams angularly of the machine to change the time of actuation of the shaft by the corresponding followers, a cam follower engaging the contour of each cam, means resiliently connecting said levers, a shaft mounted for oscillation on said support, means operatively connecting one of said levers to said shaft for oscillating the same as the machine rotates, and operative connections between said shaft and the finger for moving the latter into and out of engagement with the container.

8. In a rotary container labeling machine having a moving horizontal container support, the combination of a finger for holding a label on the container, a pair of stationary cams having peripheral cam contours in planes parallel to the plane of said support, a shaft journaled on said support, a pair of levers on said shaft, each having a follower engaging the contour of a different one of said cams, means operatively connecting at least one of said levers to said shaft, and operative connections between said shaft and the finger whereby the latter is moved into and out of engagement with the container as the machine rotates.

9. In a rotary container labeling machine hav-

ing a moving horizontal container support, the combination of a finger for holding a label on the container, a pair of stationary cams having peripheral cam contours in planes parallel to the plane of said support, a shaft journalled for oscillation on the support, a lever fixed on said shaft and engaging one of said cams for operation thereby, a second lever journalled on said shaft and engaging the other cam for independent operation thereby, a spring interposed between said levers, and operative connections between said shaft and said finger, whereby rotation of said machine causes said levers to actuate said shaft in accordance with the contours of the corresponding cams to move said finger into and out of engagement with the container.

10. In a rotary container labeling machine having a moving horizontal container support, the combination of a finger for holding a label on the container, a pair of stationary cams having peripheral cam contours in planes parallel to the plane of said support, a shaft journalled for oscillation on the support, a lever fixed on said shaft and engaging one of said cams for operation thereby, a second lever journalled on said shaft and engaging the other cam for independent operation thereby, a spring connecting said levers for urging them into resilient engagement with the corresponding cams, and operative con-

nections between said shaft and said finger, whereby rotation of said machine causes said levers to actuate said shaft in accordance with the contours of the corresponding cams to move said finger into and out of engagement with the container.

11. In a rotary container labeling machine having a moving horizontal container support, the combination of a finger for holding a label on the container, a pair of stationary cams having peripheral cam contours in planes parallel to the plane of said support, a horizontal shaft journalled for oscillation on said support, means operatively connecting said shaft to the finger, a vertical second shaft journalled for oscillation in the support, means operatively connecting said second shaft to said first shaft, a lever fixed on said second shaft and engaging one of said cams at its free end, a second lever journalled on said second shaft and engaging the other of said cams at its free end, and a spring interposed between said levers for urging them simultaneously into engagement with the corresponding cams, whereby said shaft and finger are oscillated jointly by said cams during rotation of the machine to engage and disengage said finger with the container.

KURT MANRODT.
